UNITED STATES PATENT OFFICE.

STEPHEN F. BRIGGS AND EDWARD N. JACOBI, OF MILWAUKEE, WISCONSIN, ASSIGNEES
TO BRIGGS & STRATTON COMPANY, OF MILWAUKEE, WISCONSIN, A CORPORATION
OF WISCONSIN.

LIGHTING AND IGNITION SWITCH.

Application filed December 13, 1915. Serial No. 66,459.

To all whom it may concern:

Be it known that we, STEPHEN F. BRIGGS and EDWARD N. JACOBI, citizens of the United States, and residents of Milwaukee, 5 in the county of Milwaukee and State of Wisconsin, have invented new and useful Improvements in Lighting and Ignition Switches, of which the following is a description, reference being had to the accompanying drawings, which are a part of this specification.

This invention has for its object to provide a key controlled lighting switch combined with a pole reversing ignition switch, 15 the removal of the key serving to lock the switch with the ignition circuit open and against a change in the connections made in the lighting circuit, and the return of the key and its turning in the lock to unlock the 20 switch serving to reverse the polarity of the battery ignition circuit.

Another object of the invention is to provide such a switch with the parts so arranged that they occupy a small space and 25 will still afford the proper insulation, the construction being inexpensive to manufacture though neat and ornamental in its appearance.

With the above and other objects in view 30 the invention consists in the lighting and ignition switch as herein claimed and all equivalents.

Referring to the accompanying drawings, 35 in which like characters of reference indicate the same parts in the different views,

Fig. 1 is a front view of a switch constructed in accordance with this invention;

Fig. 2 is a rear view thereof;

Fig. 3 is a rear view with the switch base 40 removed;

Fig. 4 is a front view of the switch base with the switch arms shown in dotted lines in the "on" position of the switch for lighting the strong headlights and the taillight, 45 and showing the ignition switch brushes bearing on the live segments to establish the ignition circuit, as when the key is in place;

Fig. 5 is a similar view showing the change which takes place in removing the key, the ignition switch brushes having been shifted to the dead segments, and showing the insulating connector for moving them;

Fig. 6 is a transverse sectional view of the switch on the plane of line 6—6 of 55 Fig. 5;

Fig. 7 is an enlarged detail sectional view of the switch base on the plane of line 7—7 of Fig. 4;

Fig. 8 is a rear view of the switch with the base and switch member removed and the lock bolt shown in the locked "off" position;

Fig. 9 is a rear view of the switch handle with the locking cam sectioned on the plane of line 9—9 of Fig. 6, and showing the ratchet engagement thereof;

Fig. 10 is a perspective view of the locking cam;

Fig. 11 is a perspective view of the key guide;

Fig. 12 is a detailed view of the key; and,

Fig. 13 is a detail view of the insulating connector for moving the pole reversing ignition switch brushes.

In these drawings 15 indicates a switch front plate adapted to be secured to the cowl dash or other switch board of an automobile, and 16 is the switch handle centrally mounted therein and adapted to have a limited oscillating movement to assume the various operative positions for controlling the lighting circuit, such positions being preferably marked on the front plate, as shown in Fig. 1. A flanged cylindrical casing or shell 17 is secured to the back of the front plate 15 with a disk 18 therebetween, said disk being provided with an opening registering with the opening in the front plate, through which the switch handle passes, and an inturned flange 19 around the opening. A switch member consisting of an insulating disk 20 carrying one or more sheet metal spiders 21 with radial spring contact arms is secured to the switch handle by means of screws 22, and a metal disk 23 on the insulating disk 20 forms a bearing plate engaging the edges of the inturned flange 19 to prevent the withdrawal of the switch handle. The limitation in the movement of the switch handle is produced by an inwardly bent lug 24 cut from the flange 19 and projecting into a recess 25 in the switch handle 16, the engagement of said lug with the end walls of the recess limiting the movement of the switch handle 100 in either direction.

A disk-like switch base 26 fits in the rear end of the casing 17 and is held firmly in place by suitable means such as screws 27, its inner surface being provided with a 110

series of concave depressions 28 to receive the convex ends of the spring fingers of the spider in the different operative positions of the switch, said convex ends of the spider arms riding over the surface of the switch base from one depression to the next in changing the switch from one position to another. At desired positions these depressions are made in the ends of metal contact studs 29, 30, 31 and 32 respectively which pass through the insulating base 26 and have screws and washers at their outer ends to form binding posts. The position and number of these contact studs and the position and number of the spring arms of the spider may be varied to suit the requirements of the particular use for which the switch may be designed. As shown, however, the contact stud 29 is intended for connection with the taillight, the contact stud 30 for connection with the bright headlights, the contact stud 31 for connection with the dim headlights, and the contact stud 32 for connection with the battery, and the spider arms are so arranged that in the "on" position of the switch, as shown by dotted lines in Figs. 4 and 5, they engage the battery contact 32, the bright headlight contact 30 and the taillight contact 29, but do not engage the dim headlight contact 31. Thus the bright headlights and the taillight are connected with the battery. A movement of the switch one point to the left to the dim position removes the connection with the bright headlight contact and substitutes connection with the dim headlight contact, connection with the taillight and the battery continuing so that the dim headlight and the taillight are connected with the battery, but in the third position of the switch, or the "off" position, by a further movement of one point to the left, connection with the battery is removed so that none of the lights are connected therewith.

The switch handle may be locked in any of its positions by the act of turning and removing a key 33 which fits through a key opening 34 in the end of the switch handle 16. A key guide 35 fits in a bore of the switch handle and comprises a strip of sheet metal bent to a narrow U-form with its upper ends bent outwardly and rounded to fit the bore. The narrow space between the sides of the key guide is adapted to register with the key opening 34, and the flat key 33, when inserted, fits therein with the two horns at its end passing through cut-away parts of the bottom bend of the key guide to enter a slot 36 in the end of a cam member 37. The slotted end of the cam member 37 rotatably fits in the end of the bore of the switch handle and has a central depression 38 in which the reduced inner end of the key guide fits so as to be capable of turning without turning the cam

member and being held in position thereby for guiding the insertion of the key into the slot 36. Next to the end boss-like portion of the cam member 37 which fits in the key guide bore of the switch handle is a ratchet 39 and a concentric cam 40 preferably forming integral parts of the cam member, and a spring pawl 41 secured in place in a recess of the switch handle engages the teeth of the ratchet to permit the cam member to turn only in one direction with respect to the switch handle. The cam 40 bears upon the bearing plate 23 and fits within a cross slot or Scotch yoke opening of a sliding locking bolt 42. The turning of the cam member 37 by means of the key engaged therewith causes the cam 40 to reciprocate the locking slide 42 so as to project first one end and then the other beyond the switch handle and into engagement with suitable locking notches 43 in the flange 19, when the key guide 35 is in position to register with the key opening 34. Notches 44 in the edges of the key and an enlargement at the center of the key opening 34 permit the key to be turned after it is properly entered and engaged with the cam member 37 though such turning may only be in the direction permitted by the ratchet, and the cam which reciprocates the sliding lock bolt is so positioned that when the slot 36 of the cam member is at right angles to the plane of the key opening the sliding bolt is within the confines of the switch member, but in the intermediate positions when the groove 36 is in the plane of the key opening the locking bolt is projected at one end or the other through one of the openings 43, thus locking the switch handle against turning.

At its other end the cam member 37 is provided with a flange 45 which fits within a central slot 46. A connecting member 47 of insulating material, shown as a fiber disk, has diametrically opposite notches 48 engaged with a pair of concentric rotatably mounted brush arms 49 which are insulated from each other and sweep over a set of contact segments 50 and 51 respectively. The segments 51 have no electrical connection and the segments 50 which are diametrically opposite have electrical connection with binding post studs 52 intended for connection with the terminals of an ignition circuit.

The concentric pivotal mounting for the contact brushes 49 is most clearly shown in Fig. 7 and comprises a shouldered, flanged tubular stud 53 passing through the recessed fiber base 26 with its outer edge turned outwardly to rivet it in place against a metal strap 53' which connects with the "battery" binding post 32. Around the reduced shouldered portion of the tubular stud 53 and confined between the flange thereof and

a metal washer 54 is the ring-shaped end of one of the contact brushes 49 which is thus electrically connected with that terminal of the battery which is connected to the "battery" binding post. An insulating tube 55 fits within the tubular stud 53, and together with an insulating washer 56 bearing on washer 54 and an insulating washer 57 bearing on the turned-over edge of the tubular stud, insulates said tubular stud from a shouldered and flanged central stud 58 which passes therethrough. The ring-shaped end of the other contact brush 49 fits around the shouldered portion and against the flanged portion of the central stud 58 and bears upon a metal washer 59 confined between the shouldered portion of the central stud and the insulating washer 56. At the outer end of the central stud 58 its edges are turned 20 outwardly against a metal washer 60 which bears against the insulating washer 57, thus riveting together the assembled parts in such a way that the two contact brushes 49 may freely swing about the same axis while 25 being thoroughly insulated from each other. Electrical connection is made with the upper contact brush through the central stud 58, a screw 61 being threaded in the outer end thereof to form a binding post there- 30 with for connection with the other terminal of the battery.

This switch construction affords control of the lighting circuits combined with a control of the ignition circuit with an effective 35 locking of the lighting switch in any of its positions with a locking of the ignition switch in its open position by the removal of the key, and having the added feature of reversing the polarity of the ignition 40 circuit each time the key is inserted and turned to unlock the switches. There is thus combined in this switch the protection against tampering with the lighting circuit, and protection against theft of the automobile by preventing the closing of the ignition 45 circuit, and a protection against pitting of contacts in the ignition circuit by the automatic reversal of direction of current there- 50 through each time the key is removed and replaced.

When the key is in place in the switch the locking bolt 42 is in an intermediate position where it will not engage any of the notches of flange 19, and consequently the 55 switch handle 16 may be turned from one position to another, making connection for lighting the bright headlights and the taillight in the "on" position, and making connection for lighting the dim headlights and the taillight in the "dim" position, and disconnecting the battery from all lights in the "off" position. In any position of the lighting switch with the key in place the ignition 60 circuit is completed by the contact brushes 49 engaging the live segments 50 respective-

ly, said brushes remaining in contact with the live segments throughout the sweep of movement of the switch handle 16 by turning with the switch handle. The positive engagement of the pawl 41 with the ratchet 70 teeth 39 causes the cam member 37 to move with the switch handle when the latter is turning in one direction and the spring action of the pawl 41 is sufficiently stiff to cause the cam member 37 to turn with the 75 switch handle when the latter is moved in the other direction.

When, however, the key is turned in the switch handle to a position in line with the keyhole so that it may be withdrawn therefrom, the turning of the cam member 37 incident thereto causes the locking bolt 42 to be forced by the cam 40 into engagement with one of the notches 43, whatever the position of the switch handle may be, and 80 the turning of the insulating connector 47 which is keyed on said cam member causes the contact brushes 49 to move off of the live segments 50 and onto the dead segments 51, thus opening the ignition circuit. The 85 switch being locked, no change can be made therein until the key is inserted and turned in the same direction as before, the ratchet preventing its turning in the other direction. In turning the key the contact brushes 90 95 49 are again moved into contact with the live segments 50, but as they have been moved just one half turn their positions have been transposed relative to the live contacts forming the terminals of the ignition circuit, and as said contact brushes form terminals of the battery circuit the direction of flow of current through the ignition circuit is reversed, and each time the key is removed and inserted such reversal will take place so that pitting of vibrator or interrupter contacts will be minimized or avoided entirely.

From the foregoing it will be understood that the switch mechanism of this invention 100 combines with the stationary base part consisting of the casing 17 and terminal head 26; a controller consisting of the contacts 21 with their co-operating contact studs 29, 30, 31 and 32; and also a second controller 105 which is concentric with the first controller and consisting of contact brushes 49 and their co-operating segments 50; and that the cam member 37 constitutes a spindle positioned concentrically within the first mentioned controller for operating the second controller; that the handle 16 serves to operate the first mentioned controller; that the key 33 constitutes a removable handle positioned concentrically within the first mentioned handle for operating the second controller; that the locking bolt 42 constitutes a means for locking the first mentioned controller against oscillation when it is in the 110 "off" position; and the cam 40 constitutes a 115 120 125 130

means operated by the removable handle for disabling the locking means.

It is obvious that the invention is not confined to the particular circuit connections described or to the details of construction, but that various modifications may be made coming within the scope of the invention as defined by the claims.

What we claim as new and desire to secure by Letters Patent is:

1. A switch having a rotary handle, a key adapted to fit in the handle and turn therein, a cam engaged and turned by the key, a locking bolt on the switch handle moved by the cam, and a stationary stop engaged by the locking bolt.

2. A switch having a rotary switch handle containing a cavity communicating with a key opening, a key guide comprising a strip of sheet metal bent to a U-shape with its ends turned outwardly, said key guide fitting in the cavity with the outturned ends bearing against the walls of the cavity to position the narrow space between the parallel sides of the key guide in alignment with the key opening, the bent portion of the key guide having its edges cut away to form a reduced central end portion, a cam member rotatably mounted in the switch handle and having a central socket containing the reduced end of the key guide and having a transverse slot through the walls of the socket, a flat key adapted to enter through the key opening and having a pair of spaced projections at its inner end to straddle the reduced end portion of the key guide and enter the slot of the cam member, a locking bolt slidably mounted in the switch handle and engaged by the cam, and a stationary stop engaged by the locking bolt.

3. A switch having a rotary switch handle containing a cavity communicating with a key opening, a key guide comprising a strip of sheet metal bent to a U-shape with its ends turned outwardly, said key guide fitting in the cavity with the outturned ends bearing against the walls of the cavity to position the narrow space between the parallel sides of the key guide in alignment with the key opening, the bent portion of the key guide having its edges cut away to form a reduced central end portion, a cam member rotatably mounted in the switch handle and having a central socket containing the reduced end of the key guide and a transverse slot through the walls of the socket, a flat key adapted to enter through the opening and having a pair of spaced projections at its inner end to straddle the reduced end portion of the key guide and enter the slot of the cam member, a locking bolt slidably mounted in the switch handle and engaged by the cam member, a stationary stop engaged by the locking bolt,

ratchet teeth on the cam member, a spring pawl on the switch handle engaging the ratchet teeth, a switch member secured to the switch handle, switch arms carried thereby, and a switch base having contacts engaged by the switch arms.

4. In a switch, a suitably mounted switch handle, a lighting switch controlled thereby, a lock for the switch handle, a key fitting in the switch handle and adapted to be turned for operating the lock and confined in place while the switch handle is unlocked, and an ignition switch operated by the turning of the key.

5. In a switch, a switch handle, a switch mechanism operated thereby, a lock for the switch handle, a lock operating member, a key for turning said member, and a pole reversing switch operated by the key produced turning movements of the lock operating member.

6. In a switch, a switch handle, a switch mechanism operated thereby, a lock for the switch handle, a cam member for operating the lock, a removable key engaging the cam member for turning the same, a ratchet for preventing the turning of the cam member in one direction, and a pole reversing switch operated by the cam member.

7. In a switch, a switch handle, a lock therefore, a switch mechanism operated by the switch handle, key controlled means for operating the lock, a pair of concentrically mounted contact brushes insulated from each other, an insulated connector on the lock operating means engaging the contact brushes, and stationary contacts in the path of the contact brushes.

8. In a switch, a casing, a switch handle mounted therein, a sliding bolt on the switch handle adapted to engage the casing to lock the switch handle, a cam member rotatably mounted in the switch handle and having a cam engaging the sliding bolt to move it into and out of its locking engagement, ratchet teeth on the cam member, a spring pawl on the switch handle engaging the ratchet teeth, a key adapted to turn and lock within the switch handle and engaging the cam member to cause the cam member to turn therewith, a lighting switch operated by the turning of the switch handle, and a pole reversing ignition switch operated by the turning of the cam member.

9. In a switch, a casing, a switch handle mounted therein, a key-turned cam member mounted in the switch handle, a lock member operated by the cam member for locking the switch handle, an insulating base for the casing, a flanged, tubular stud passing through the insulating base, a flanged stud passing through the tubular stud and insulated therefrom, contact brushes rotatably mounted on the flanged portions of both studs and insulated from each other, sta-

tionary contacts on the insulating base engaged by the contact brushes, an insulating connector connecting the contact brushes with the cam member, means for making 5 electrical connection with the studs, a switch member carried by the switch handle, and switch contacts in the insulating base engaged thereby.

10. In a switch, a casing, a switch handle mounted therein, a lock for the switch handle, a key-turned cam member for operating the lock, an insulating base for the casing, contact brushes concentrically mounted on the insulating base, means for 15 making electrical connection therewith, stationary contact segments on the insulating base engaged by the contact brushes, said contact brushes being bent to form arched portions, a rib on the end of the cam member, an insulating disk having a slot receiving the rib and having notches in its edge engaging the arched portions of the contact brushes, a switch member carried by the switch handle, and stationary contacts in 25 the insulating base engaged by the switch member.

11. In a switch, a switch handle, a switch mechanism operated thereby, a lock for the switch handle, a key for operating the lock 30 by a turning movement thereof, and a pole reversing switch operated by the turning of the key.

12. In a combination switch, a handle mounted to turn, a switch turned thereby, a driver mounted to turn in the handle, a detent connection between the handle and the driver, a second switch driven by the driver, a terminal head having contacts engaged by the two switch members, the contacts for the second switch member being of sufficient 40 length to remain in engagement with the second switch member throughout the range of movements of the handle.

13. In a combination switch, a handle mounted to turn, a switch turned thereby, 45 detents for yieldingly holding the switch member in its various positions, a driver mounted to turn in the handle, a ratchet connection between the handle and the driver, a second switch driven by the driver, 50 a terminal head having contacts engaged by the two switch members, the contacts for the second switch member being of sufficient length to remain in engagement with the second switch member throughout the range 55 of movement of the handle.

In testimony whereof, we affix our signatures, in presence of two witnesses.

STEPHEN F. BRIGGS.
EDWARD N. JACOBI.
